UNITED STATES PATENT OFFICE.

MAX L. BREDE, OF CHICAGO, ILLINOIS.

DESIGN FOR A DRINKING-GOBLET.

44,605.

Specification for Design.

Patented Sept. 2, 1913.

Application filed May 29, 1913. Serial No. 770,759. Term of patent 14 years.

To all whom it may concern:

Be it known that I, MAX L. BREDE, a resident of Chicago, in the county of Cook and State of Illinois, have invented a new, original, and ornamental Design for a Drinking-Goblet, of which the following is a full, clear, and exact description, reference being had to the accompanying drawing, forming a part thereof.

Figure 1 is a perspective of a goblet showing my new design. Fig. 2 is a section taken on line 2—2 of Fig. 1.

The goblet is characteristic in having annular series of elliptic or olive-shaped recesses *a* cut on the exterior of the body *b*

of the goblet, the cuts of one series being alternately placed between the others and the interior surface of the goblet has creases *c* to give a ribbed effect to the body of the tumbler. The cuts *c* are disposed between said creases and the body is mounted upon a stem *d*.

I claim:

The ornamental design for a goblet, as shown.

MAX L. BREDE.
